Charles G. Henley.

UNITED STATES PATENT OFFICE.

EMIL J. SANER, OF WEST NEW YORK, NEW JERSEY.

AUTOMOBILE-SIGNAL.

1,399,524.

Specification of Letters Patent.

Patented Dec. 6, 1921.

Application filed September 1, 1920. Serial No. 407,486.

To all whom it may concern:

Be it known that I, EMIL J. SANER, a citizen of the United States, and a resident of West New York, in the county of Hudson and State of New Jersey, have invented certain new and useful Improvements in Automobile-Signals, of which the following is a specification.

The object of my invention is to provide a simple and inexpensive device for use on automobiles for signaling to automobiles and other vehicles to the rear, of an intention to stop or turn. The device includes a number of arrows or semaphores which fold into overlapping position within a casing when out of use and which are projected outwardly in fan shape when set for signaling. The device includes a simple lever arrangement for quickly projecting the signaling member in fan shape and for holding them in that position until released. The signal operating device is so arranged and operated that it will operate the semaphores equally well whether the apparatus is arranged on the right-hand side or left hand side of the automobile, so that the apparatus is adapted to be changed from one side to the other without altering the operating device.

My improvements also include a simple, adjustable bracket for attaching the apparatus to the dashboard of an automobile.

In the drawing forming part of this application,

Figure 1 is an elevation of my signaling device without the bracket, showing the same positioned for signaling at the left hand side of an automobile.

Fig. 2 is a similar view showing the semaphores down or closed.

Fig. 3 is an enlarged view of the lever device for operating the semaphores, one half of the casing being removed to expose the operating parts.

Fig. 4 is a detail view showing lugs on the several semaphore blades for causing the latter to pick up or engage one another when overlapping, to effect the folding or closing of the several blades.

Fig. 5 is an end view of the apparatus,

Fig. 6 is a vertical sectional view,

Fig. 7 is a plan view, and

Fig. 8 is a sectional view taken on the line 8—8 of Fig. 4,

Fig. 9, is an edge view of the signal casing,

55

Fig. 10 is a face view of the attaching bracket,

Fig. 11 is an elevation showing the device attached on the bracket, and

Fig. 12 is a plan view of the attaching bracket.

I prefer to use a compact form of casing for inclosing the signal members and their operating devices and for this purpose I have provided parallel plates 1, 2, connected by screws 3 and comprising the wider portion 4 for inclosing the operating devices, and the long narrower portion 5 for inclosing the semaphores. One side of the portion 5 is closed by a wall 6 and the opposite side 70 is left open to allow the semaphores or signal blades to move in and out.

The semaphore blades are shown herein of arrow shape and five in number, though there may be a greater or lesser number of these members if desired. They are all pivoted to swing on a common arbor 7 which passes through the walls of the casing. There is a lever pivoted on an axle 13 and one arm 14 of this lever projects at one side 80 of the casing and is provided with an operating handle 15 which is within easy reach of the driver of the automobile when the apparatus is attached in place.

The other arm 16 of this lever is pivotally connected at 17 with one end of a link 18 and the other end of this link is pivotally connected at 19 with an extended or lever arm 20 of the master semaphore blade 8. The operating lever is thus connected directly with only one of the semaphore blades and the remaining blades are actuated by that (master) blade. The operating lever arm 14 is adapted to pass a stop piece 21 on the casing and to engage behind either of 90 the edges 22, 23 of the stop to lock the lever in either of its extreme positions. The operating lever serves to move the master blade into the position shown in Fig. 1 at right angles to the part 5 of the casing, or to the 100 position shown in Fig. 2 where it lies inclosed or retracted within the casing.

The master blade is provided with members which engage with or pick up the several other blades in successive order when 105 the master blade is swung into signaling posi-

tion; and these members cause the remaining blades to move into position to form a complete signal of fan shape. The engaging member 24 extending at right angles from one edge (bottom in Fig. 3), of the master blade 8 projects across the path of the signal blade 9 which lies next to the master blade but not far enough to engage any of the other blades. The projection 25 on the master blade is offset farther than the projection 24 and it is long enough to reach over and engage the edge of the blade 10. Likewise, the projection 26 is offset still farther and is long enough to engage the edge of the blade 11; and the projection 27 is still farther offset and it is long enough to engage the blade 12. The master blade also has a projection 28 at its opposite edge which engages the opposite edges of all the other blades in one direction. I prefer to arrange individual lugs or projections 29-32 on the several blades each one adapted to engage the edge of an adjacent blade when moving toward the closed position so that all the strain will not come on the projection 28 of the master blade.

The master blade insures the opening of the several blades to fan shape when the several blades move upwardly in opening because then the master blade operates against the gravity of the other blades. I provide a block 33 in the casing having stepped shoulders 34 against which the upper edges of the several blades individually engage and this block arrests the blades in fan shape formation.

I have provided flexible connections between the outer ends of the several blades to hold these outer ends in the desired formation when extended and which will leave the blades free for folding. This consists of a cord or string 35 tied through a hole 36 in each blade at the outer end, and between the points of tying the cord is of the required length to hold the outer ends of the blades from separating beyond the fan shape indicated. As this cord is flexible it does not interfere with the folding of the blades upon each other when they are closed and it also prevents rattling of the outer ends of the blades against each other.

Any means may be employed for attaching the device in position on an automobile, but herein I have shown a device consisting of an angle plate 37 against one web 38 of which the casing may be clamped by means of the screws 3. The casing may be attached to the member 37 in either of two positions, so that the part 5 of the casing or frame may be arranged to extend downwardly when the device is either on the left hand side or the right hand side of the automobile. When the bracket is reversed from one side to the other, the casing may be released by removing the screws 3 and the casing may then

be turned over and reclamped in the opposite position. Thus the blades may be directed downwardly when in closed position regardless of which side of the automobile the device is attached to.

The bracket member 37 is attached to the companion bracket member 39 by a bolt 40 engaging in an aperture 41 in the bracket member 39 and by a bolt 41 in the arcuate slot 42 in the member 39. These bolts permit the bracket member 37 to be adjusted in the arc of a circle to permit the member 37 to be placed upright regardless of the angle of inclination of the member 39. The latter is screwed or bolted to the dash board of the automobile and as the dashboards in different vehicles have different angles of inclination the adjustment above referred to makes it possible to adapt the device to any dashboard.

Operation: When the device is attached for left hand signaling as shown in Figs. 1 and 2 the portion 5 of the casing hangs downwardly and when the signal blades are in closed position they are inclosed therein. The operating lever, arm 14, engages at this time behind the shoulder 23 of the block 21. If it is desired to set the signal to signal to approaching automobilists the operator grasps the handle 15 and moves the lever arm 14 sideways enough to pass the shoulder 23 and then moves the lever arm upwardly and moves it into locking engagement of the shoulder 22 of the block 21. During this operation of the lever arm 14 the arm 16 operates through the link 18 to swing the end 20 of the master blade downwardly and the outer or signaling portion of this blade upwardly. As the master blade moves upwardly (outer portion) the projection 24 comes into contact with the blade 9 and from then on these blades move upwardly together. Just after the projection 24 engages the blade 9 the projection 25 engages the blade 10, and in like manner the projections 26, 27, successively engage the blades 11 and 12 respectively, and all blades then move upwardly until the master blade reaches a horizontal position and the several blades are positioned in fan shape. In this position the blades are visible at the rear of the automobile and indicate that the latter is about to stop or turn. To retract the signal the lever arm 14 is released from the shoulder 22 and it is moved downwardly. This operation swings the master blade downwardly and if the other blades fail to fall by gravity the several projections 28-32 come into action on adjacent blades and all blades then move down with the master blade, overlapping as they do so, and finally stopping inside the casing portion.

To position the device for right hand signaling, it is only necessary to reposition the brackets and reverse the signal casing on

the brackets, and the signal blades will then be projected to the right instead of to the left.

When the master blade moves upwardly 5 and carries the other blades with it, the several blades come to rest against the stepped shoulders 34 of the stop block 33. While the blades are resting against this block they cannot be shaken upwardly out of their 10 formation by jarring of the automobile.

Having described my invention, what I claim is:

1. A signal device of the class described comprising a casing, a plurality of signal 15 blades pivoted in said casing and adapted to be swung into and out of said casing, manually controlled means for actuating one of said blades to project the same into signaling position and means on said last mentioned 20 blade for successively engaging the remaining blades to cause the latter to be operated with said operated blade and a stepped abutment member against which said blades are adapted to rest in fan shape 25 relation when in signaling position.

2. A signal device of the class described comprising a casing, a plurality of signal blades pivoted in said casing, manually controlled means for actuating one of said 30 blades to project it into signaling position and projections on said actuated blade offset different extents and adapted to successively engage the several blades as the

said actuated blade moves into signaling position whereby the several blades are projected in fan shape formation. 35

3. A signal device of the class described comprising a casing, a plurality of signal blades pivoted in said casing, manually controlled means for actuating one of said 40 blades to project it into signaling position, means on said latter blade for engaging the other blades to cause the several blades to be projected in fan shape formation, and pliable means connecting the outer free ends of 45 said blades for the purpose set forth.

4. A signal device of the class described comprising a casing, pivoted signal blades therein and means for operating them, and means for attaching said casing to a vehicle comprising a bracket member having right angle plates, one of which is adapted 50 to be attached to the vehicle and the other having an arcuate slot and an aperture concentrically located, and a second bracket 55 member having a plate adapted to be secured to the second plate portion of the first bracket member by means of bolts passing through said aperture and said arcuate slot, said second bracket member having a second plate at right angles to the first portion 60 and against which said casing is bolted.

Signed at the city, county, and State of New York, this 21st day of August, 1920.

EMIL J. SANER.
